FOREIGN PATENT DOCUMENTS

GB 2451806 8/2007

Primary Examiner — Philip S Hyder

(74) Attorney, Agent, or Firm — Dennis D. Brown;
Brown Patent Law, P.L.L.C.(57) **CLAIM**

The ornamental design for the shelf spacing tool as shown and described.

DESCRIPTION

FIG. 1 is a front perspective view of the shelf spacing tool, showing our new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top view thereof.

FIG. 7 is a bottom view thereof.

FIG. 8 is a rear perspective view thereof.

FIG. 9 is a partially retracted view thereof.

FIG. 10 is a fully retracted view thereof.

FIG. 11 is an enlarged view of the section 11 thereof shown in FIG. 1.

FIG. 12 is an enlarged view of the section 12 thereof shown in FIG. 2.

FIG. 13 is an enlarged view of the section 13 thereof shown in FIG. 4.

FIG. 14 is an enlarged view of the section 14 thereof shown in FIG. 5; and,

FIG. 15 is an enlarged view of the section 15 thereof shown in FIG. 8.

The broken line portions of the drawings are included to show portions of the article that form no part of the claimed design.

1 Claim, 13 Drawing Sheets(56)
